(57) **CLAIM**

The ornamental design for a lamp fitting assembly, as shown and described.

DESCRIPTION

FIG. 1 is a first perspective view showing a first part of the lamp fitting assembly showing my new design;

FIG. 2 is a second perspective view of the first part of the lamp fitting assembly;

FIG. 3 is a front view of the first part of the lamp fitting assembly;

FIG. 4 is a left side view of the first part of the lamp fitting assembly;

FIG. 5 is a top plan view of the first part of the lamp fitting assembly;

FIG. 6 is a bottom plan view of the first part of the lamp fitting assembly;

FIG. 7 is a first perspective view showing a second part of the lamp fitting assembly showing my new design;

FIG. 8 is a second perspective view showing a second part of the lamp fitting assembly showing my new design;

FIG. 9 is a front view of the second part of the lamp fitting assembly;

FIG. 10 is a left side view of the second part of the lamp fitting assembly;

FIG. 11 is a right side view of the second part of the lamp fitting assembly;

FIG. 12 is a bottom plan view of the second part of the lamp fitting assembly;

FIG. 13 is a top plan view of the second part of the lamp fitting assembly;

FIG. 14 is a first perspective view showing the first part coupling with the second part of the lamp fitting assembly; and,

FIG. 15 is a second perspective view showing the first part coupling with the second part of the lamp fitting assembly.
